DUPLEX COMPOUND DRAFT GEAR

Application filed January 10, 1930. Serial No. 419,773.

This invention relates to a duplex compound draft gear, and has for its general object and purpose to provide a simply constructed and efficiently functioning draft gear for use in connection with rail and highway vehicles, such as locomotives, cars, automobile trucks and the like. 55

It is also one of the important objects of the invention to provide a draft gear which 10 will effectively absorb shocks resulting from buff and pull, which is composed of a minimum number of parts cooperatively assembled whereby there will be a minimum of wear and wherein the possibility of fracture 15 or bursting of the gear will be obviated. Our new draft gear has a minimum of non-production weight as compared with draft gears now in general use, wherein a large percentage of the weight is in the housings 20 and which embody parts subject to excessive wear and liability of fracture and which do not directly function for the purpose of yieldingly resisting relative movement and absorbing shock. 25

Our invention also has for its purpose to produce a draft gear having a duplex compound action when the gear is under compression and in which there occurs the combined wedging frictional and spring compression action between relatively movable parts so that there will be a maximum of absorption of shock and jar. 30

It is a further object of our invention to provide such a draft gear having both coil and elliptic springs of the laminated type which will conjointly function in both the compression and release action of the gear. More particularly, in addition to the main elliptic springs, we provide primary and 35 secondary sets of coil springs, all of which function simultaneously to produce resistance of the compression of the gear, and said springs likewise functioning simultaneously to restore the draft gear to normal condition 40 upon release of compression. 45

It is a further general object of our invention to provide such a draft gear wherein the impact stresses and strains are divided over several sets of springs acting along the axial line of the gear as well as at right 50

angles thereto so as to thereby reduce the liability of the springs acquiring a permanent set with the resultant diminution in the spring capacity or travel thereof, such as occurs when a less number of springs with greater strength are employed to perform the same work. 55

With the above and other objects in view, the invention consists in the improved duplex compound draft gear, and in the form, construction and relative arrangement of its several parts as will be hereinafter more fully described, illustrated in the accompanying drawings, and subsequently incorporated in the subjoined claims. 60

In the drawings, wherein we have illustrated several simple and practical embodiments of the invention, and in which similar reference characters designate corresponding parts throughout the several views,— 65

Figure 1 is a top plan view partly in section, showing a draft gear embodying one form of our present improvements; 70

Fig. 2 is a sectional view taken substantially on the line 2—2 of Fig. 1; 75

Fig. 3 is a detail plan view of the two side pieces of the draft gear, and

Fig. 4 is a view similar to Fig. 1 illustrating a slightly modified form of the device. 80

Referring in detail to the drawings, 5 designates the two similar end pieces or members of the draft gear which are suitably secured to the center or draft sills of the railway cars or other vehicles. Each of these end pieces includes a body plate of rectangular form 85 having an integral rectangular wall 6 projecting from one side thereof and forming an open sided housing for the reception of other parts of the gear to be presently described. The body plate of the member 5 is also centrally provided with a hollow boss 7 extending into this housing, and at the base thereof with an annular recess or seat 8 to receive one of the primary compression springs. 90

The side members 9 are each provided with upper and lower spaced walls 10 integrally connected by the longitudinally extending web 11. The intermediate or central portions 12 of these webs of the two side members are disposed in spaced parallel relation 100

while the longer end portions 13 of said webs are outwardly inclined to the opposite ends of the respective side members. Thus from reference to Fig. 1 of the drawings, 5 it will be noted that the end portions 13 of said web diverge from each other from the parts 12 thereof to the ends of the side members which extend within the housings formed by the rectangular wall 6 of the end pieces 5.

10 The side walls 10 of the members 9 at one of their ends are provided with lug extensions 14 and with recesses 15 at their opposite ends, as most clearly shown in Fig. 3 of the drawings. Also, as therein illustrated, 15 these side members when assembled are arranged in reverse position so that the lugs 14 of one of said members fit within the recesses 15 on the other member. It will thus be understood that by the provision of these co- 20 operating lugs and recesses, when one of said members moves or shifts longitudinally of the draft gear, the other complementary side member will partake of such movement. As will be later explained, this is an important 25 feature of the present invention.

Wedge blocks 16 are arranged between the flaring or diverging end portions 13 of the webs of the two side members and are of 20 rectangular external form in cross section, providing the longitudinally converging opposite frictional side faces indicated at 17 for cooperation with the inner friction surfaces 18 of the inclined web parts 13 on the side members 9.

25 The outer larger ends of the wedge blocks 16 are hollow to receive inner and outer primary compression and release springs 19 and 20 respectively. The outer spring 20 is engaged at one of its ends upon the seat 8 of the end member 5 and bears at its other end upon the wedge block 16 while the inner spring 19 bears at one end against the boss 7 of the member 5 and at its other end against the wedge block.

30 Each of the wedge blocks at its inner end is formed with an axially extending hollow guide 21 for the secondary compression and relief springs 22 and 23 respectively. The opposite ends of these latter springs surround the guides on the respective wedge blocks so that the springs are supported thereby and kept in the proper alignment to prevent buckling of said springs under compression.

35 The assembly bolt 24 extends through the hollow guides 21 and is connected at its opposite ends with the bosses or central extensions 7 on the end members 5, whereby all of the parts are retained in an assembled self-contained condition.

A main compression and relief spring generally indicated at 25 is arranged between the upper and lower walls 10 of each side member 9 at the outer side of the web 11. Each of 40 these springs is of the conventional elliptic

type, being composed of a plurality of metal spring plates or laminations superimposed upon each other and gradually increasing in length from the innermost plate which is engaged with the central part 12 of the web 11 to the outermost plate or lamination. The outer plates at their opposite ends extending within the rectangular housing walls 6 of the respective end pieces 5 and one or more of these outer plates is provided in each end thereof with an opening to receive the stud 27 of a detachable friction shoe 26. This connection is sufficiently loose to permit the end of the spring to assume a slight angular relation to the stud 27 whereby contact is maintained between the inclined face of the shoe and the wall 6 of member 5 in the relative movement between said parts. The inclined faces 28 of these shoes have sliding frictional engagement with the inner inclined faces 29 of the opposite sides of the housing wall 6 of the respective end members 5.

With the several parts above described assembled as shown in Fig. 1 and the end pieces 5 attached to the center or draft sills of the cars or vehicles, it will be readily understood that in the compression of the draft gear, the end members 5 move towards each other so that there simultaneously occurs a sliding frictional coaction of the wedge blocks 16 with the inclined web sections 13 of the two side members tending to expand or separate the latter, while the walls 6 of the end members also coact with the shoes 28 on the opposite ends of the main spring 25, thus compressing the latter. Also at the same time, the primary springs 19 and 20 are compressed, and the secondary springs 22 and 23 are also compressed. This is due to the fact that the resistance of the spring 20 is much greater than that of springs 22 and 23, and initially the end member 5 and wedge 16 together with springs 19 and 20 move as a unit relative to the members 9 and until the frictional resistance at the coacting faces 17 and 18 overcomes the resistance of springs 19 and 20. Thereupon these springs will be compressed until end members 5 move into abutting contact with wedge 16 while at the same time further inward compression of the primary springs 25 and further compression of springs 22 takes place. It will be noted that there is a relatively long travel of the wedge blocks and a gradually increasing area of frictional coaction with the side members and that all of the frictionally acting wedge parts are spring borne so that there will be no direct solid impact between the frictionally cooperating parts. Thus the compression blow received by the gear is very effectively cushioned and the shock largely absorbed thereby. Much of this shock is first taken up or absorbed by the primary and secondary coil springs, before the resistance of the main springs becomes effective.

When the gear is subjected to over solid blows, the parts 21 of the wedge members come into end to end contact at about the same time that the shoes 26 attached to the 5 ends of spring 25 contact with the body walls of the members 5.

In the release of the gear after compression, the primary, secondary and main springs, all 10 operate or function concurrently to restore the several parts of the draft gear to normal condition. Thus, both in compression and release of the draft gear, the impact stresses and strains are effectively divided, and distributed between the several parts. The 15 possibility of the springs acquiring a permanent set, thus impairing their function, is obviated. It will also be noted that by reason of the interlocking connection between the ends of the side members 13 as heretofore explained, 20 variation in the coefficient of friction between the web parts 13 of these members and the wedge blocks which might cause one of these side pieces to shift or move longitudinally with respect to the other is effectually prevented. 25

Preferably, the end edges of the walls 6 of the end pieces 5 are rounded or convex as indicated at 30 so that they will not cut or dig into the faces of the center or draft sills upon 30 which the gear is mounted.

Another feature of advantage in our improved gear is the ease and facility with which wear and lost motion may be compensated. This may be readily done without 35 removing the side plates and the wedge blocks, by merely inserting additional leaves or plates in the main springs 25 associated with each of the side members so that the original capacity of these springs and extent 40 of travel of the parts with which they are associated will be restored.

In Fig. 4 of the drawings, we have shown a slightly modified construction, in which at one end of the draft gear, the end piece 5 and the wedge block 16' are integrally formed in a single casting, and one set of the primary coil springs is eliminated. The draft gear will nevertheless, function in a satisfactory manner, but at the opposite end thereof where the primary spring set is used in conjunction with the separate end member and wedge blocks, provision is made for twice the length of relative movement between the end member and wedge block than is the case in the 50 construction of Fig. 1, as will be readily noted from a comparison of the latter figure with Fig. 4 of the drawings.

We are aware of various prior art devices 55 employing frictional wedging members in combination with compression springs, and more particularly, in one of these draft gears of the prior art, the compression springs resisting the action of the frictional wedging members are arranged at right angles to the 60 line of buff and pull. This type of draft gear

differs from the other well known prior art gears, in that instead of the blow being directly received by the housing enclosing the frictionally coacting wedging parts, it is first cushioned by the angularly arranged compression springs. However, this latter type of gear has met with serious objections, since the center or draft sills of the under frame of the car body or other structure to which the gear may be applied must be perforated to receive the rod which carries and compresses the springs. Also the springs or necessary accessory parts are located outside of the draft or center sills so that when it becomes necessary to remove the draft gear from the car for inspection, adjustment, repairs or renewals, it is necessary to first remove this rod and the springs together with the connecting parts. In the other conventional forms of draft gears, on the contrary, the entire gear may be removed as a unit from between the draft and center sills with the coupler and the coupler yoke, without dismantling of any of the draft gear parts. 70 75 80 85 90 95 100 105 110 115 120 125 130

In our present invention, it will be noted that we provide a cushioning means between the wedge blocks and the side and end members, in the form of the main compression and relief springs so that we obtain the desired cushioning action in the operation of the wedge and side members and relieve the end members of the draft gear of the destructive effects of a direct shock by the insertion of the main springs between said side members and the end pieces. This results from the fact that the side members have contact with the central portions of the main springs, while the end members contact with the end portions of said springs. At the same time, it will be observed that this cushioning means is a part of the draft gear proper, and is adapted to be placed in the coupler yoke for application as a unit therewith between the draft or center sills, or removed from the same without necessitating the disconnection of any supplementary gear parts before detachment can be effected. 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

From the foregoing description considered in connection with the accompanying drawings, the construction, manner of operation and several advantages of our improved duplex compound draft gear will be clearly understood. We have herein illustrated and described several practical and satisfactory embodiments of the essential features of our invention. It will however, be understood that the same are also susceptible of embodiment in various other alternative mechanical structures, and we accordingly reserve the privilege of resorting to all such legitimate changes therein as may be fairly considered within the spirit and scope of the invention as claimed. 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

We claim:

1. In a spring and friction draft rigging, 130

the combination of two end pieces and two wedge blocks moved by the respective end pieces, each end piece having inclined surfaces, a cushioning and relief spring interposed between the two wedge blocks, two side pieces contacting at one of their ends with one wedge block and at their other ends with the other wedge block, two main springs, one bearing against each side piece, means on the ends of each main spring having slidable frictional engagement with the inclined surfaces of said spaced end pieces and placed under compression in movement of the latter towards each other whereby, when the end pieces are moved under compression, the main springs will be compressed by the combined movement of the wedge blocks and the end pieces, and when the end pieces are released, the wedge blocks will be separated by the cushioning and relief spring, and the main springs will be released by a combined movement of the wedge blocks and the end pieces.

2. In a draft gear, end members each having inclined surfaces, wedge blocks movable with the end members towards each other, side members having frictional sliding engagement at their opposite end portions with the opposite sides of the respective wedge blocks to be expanded thereby, a cushioning and relief spring interposed between the wedge blocks and yieldingly urging the same to a normal position with respect to said side members, and main leaf springs having bearing engagement against the central portions of said side members and having means at their opposite ends contacting with the inclined surfaces on the respective end members, whereby upon compression movement of the latter, said main leaf springs are placed under compression by the combined expansion movement of the side members under the action of the wedge blocks and by the movement of said inclined surfaces of the end members.

3. In a draft gear, end members each having inclined surfaces, a wedge block associated with each end member, primary cushioning and relief springs interposed between the end members and the wedge blocks, a secondary cushioning and relief spring interposed between the wedge blocks, side pieces frictionally engaged at their opposite end portions against opposite sides of the respective wedge blocks, and main leaf springs bearing against the central portions of said side members and coacting at their opposite ends with the inclined surfaces of the respective end members whereby said main springs are placed under double compression at their centers and opposite ends in the combined movement of the wedge blocks and end members.

4. In a draft gear, two wedge blocks, side members having frictional sliding engagement at their opposite end portions against

opposite sides of the respective wedge blocks, an end member associated with each wedge block to move the latter towards each other upon compression, each end member having inclined surfaces, a cushioning and relief spring interposed between said wedge blocks urging the same to normal position, and a main spring associated with each of the side members and resisting expansion thereof in the compression movement of the wedge blocks, each main spring consisting of a plurality of superimposed spring leaf laminations, and means carried by each end of each main spring coacting with one inclined friction surface on one of the end members whereby said main springs are placed under dual compression at their centers and their opposite ends in the combined compression movement of the end members and the wedge blocks relative to said side members.

5. In a draft gear, two wedge blocks, side members having frictional sliding engagement at their opposite end portions against opposite sides of the respective wedge blocks, an end member associated with each wedge block to move the latter towards each other upon compression, each end member having inclined surfaces, a cushioning and relief spring interposed between said wedge blocks urging the same to normal position, and a main spring associated with each of the side members and resisting expansion thereof in the compression movement of the wedge blocks, each main spring consisting of a plurality of superimposed spring leaf laminations, and a detachable shoe connected with each end of each main spring and said shoes respectively coacting with an inclined friction surface on one of the end members whereby said main springs are placed under dual compression at their centers and their opposite ends in the combined compression movement of the end members and the wedge blocks relative to said side members.

6. In a draft gear, the combination of a pair of longitudinal members transversely movable towards and from each other and each having inclined plane surfaces at its opposite ends, wedges cooperating with said inclined surfaces, end members for transmitting longitudinal thrust to the wedges, main springs bearing against the outer sides of said longitudinal members, and said end members including parts cooperating with means on the opposite ends of the main springs to place the said springs under compression and cushion the impact of the wedges against said inclined surfaces.

7. In a draft gear, end members each having inclined surfaces, a wedge block associated with each end member, primary cushioning and relief springs interposed between the end members and the wedge blocks, a plurality of secondary cushioning and relief springs interposed between the wedge blocks,

side pieces frictionally engaged at their opposite end portions against opposite sides of the respective wedge blocks, and main leaf springs bearing against the central portions of said side members and coacting at their opposite ends with the inclined surfaces of the respective end members whereby said main springs are placed under double compression at their centers and opposite ends in the combined movement of the wedge blocks and end members.

In testimony that we claim the foregoing as our invention, we have signed our names hereto.

JOHN E. MUHLFELD.
JOSEPH GUTTERIDGE.
